UNITED STATES PATENT OFFICE.

DWIGHT WILSON BENNETT, OF SOMERTON, PENNSYLVANIA.

HOTBED-SASH.

1,024,113.

Specification of Letters Patent. Patented Apr. 23, 1912.

Application filed June 19, 1911. Serial No. 633,934.

To all whom it may concern:

Be it known that I, DWIGHT WILSON BENNETT, a citizen of the United States, residing at Somerton, in the county of Philadelphia and State of Pennsylvania, have invented certain new and useful Improvements in Hotbed-Sash; and I do declare the following to be a full, clear, and exact description of the invention, such as will enable others skilled in the art to which it appertains to make and use the same.

This invention relates to improvements in glass roofs or hot bed sash.

The main object of the invention is to provide means for securing the panes of glass in such a manner that substantially no shadows will be thrown by said securing means.

Another object is to provide simple and efficient glass securing means so constructed that a broken pane may be removed and replaced very quickly, thereby enabling a high temperature to be maintained under the sash with the outside temperature at a low point.

Another object is to provide a hot bed sash with cushioning means for the glass which will permit the sash to be subjected to rough usage without danger of breakage.

With these and other objects in view the invention comprises certain novel constructions, combinations and arrangements of parts, as will be hereinafter more fully described and claimed.

In the accompanying drawings Figure 1 represents a plan view of a section of hot bed sash constructed in accordance with this invention. Fig. 2 is an enlarged transverse section thereof taken on line 2-2 of Fig. 1.

Fig. 3 is an enlarged detail sectional view taken on a plane at right angles to Fig. 2 and on 3-3 of Fig. 2; Fig. 4 is a perspective view of one member of the clamp; Fig. 5 is a similar view of the other member.

In the embodiment illustrated, a sash frame 1 is shown of the usual rectangular construction with a plurality of panes of glass 2 mounted therein, with their edges abutting and with the strips of glass 3 arranged directly beneath the joints. These joints after being so arranged are treated to a solution of silicate of soda which renders them impervious to air and water.

The sash is preferably equipped with a double set of panes spaced apart to form an air space 4 between them. The frame 1 is

rabbeted on its upper and lower faces at its inner edge as shown at 5 and 6 to receive the glass, said recesses or rabbets being of a sufficient depth to receive the panes with their outer faces arranged flush with the upper and lower faces of the frame. Wooden fastening strips 9 are secured to the bars of the sash frame over the glass arranged in the rabbets thereof by screws 10. These strips 9 are provided in their lower faces at their edges with channels 11 for the reception of cushioning strips 12 which form a practically air and water-tight connection between the strips and the glass and also reduce the danger of breakage upon rough handling.

Clamping members, 13 and 14, such as are shown in Figs. 4 and 5 are arranged on the outer faces of the fastening strips 9 beneath the heads of the screws 10 and serve to reliably hold the parts in operative position and may be quickly assembled and disassembled when desired. The lower member or block 13 is provided with a longitudinally

extending key-hole slot 15 through which the screw 10 is passed, the lower end of said slot being countersunk as shown in Fig. 2 to provide for the yielding of said member when the wedge-like member 14 is forced into operative position.

The outer face of the member 13 is inclined as shown in Fig. 4 and the wedge-shaped member 14 which is also slotted longitudinally is engaged with the shank of the screw 10 and is provided at its outer thicker end with an upturned lug 16 which is designed to receive the blow of a light tool for tightening or loosening said member 14.

When it is desired to remove a pane for any purpose, the screws 10 need not be loosened and a light blow is struck the lugs of the wedge members of the clamps which will loosen the clamp and permit the blocks 13 to be moved relatively to the screws 10 to bring the enlarged rounded portions of the key-hole slots therein opposite the screw heads; then the clamps may be removed and the fastening strip 9 disengaged from the pane permitting it to be quickly removed and another submitted.

After the new pane has been placed in position the members of the clamp are replaced upon each other to cause them to firmly grip the fastening strip to which they are applied and securely engage it with the glass. As

105 a substitute for the central supporting bar usually used, I employ a light truss 17 which

110

stiffens the sash and provides two inches or more sunlight for every sash with practically no shadow therefrom.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention claimed.

I claim as my invention—

- 15 1. The herein described glass roof for hot beds comprising a supporting frame, a double set of panes of glass spaced from each other with the outer edges of the panes mounted in said frame and their inner edges abutting, glass strips overlapping said abutting edges and treated with a translucent coating impervious to air and water, and means for securing the edges of said panes to the frame in a water-tight manner.

2. A glass roof including a supporting frame having a plurality of panes of glass mounted therein with their meeting edges abutting, and glass strips arranged under the meeting edges of said panes and treated with a translucent solution of silicate of soda impervious to air and water.

3. A glass roof including a supporting frame having a plurality of panes of glass mounted therein with their meeting edges abutting, said panes lying in the same horizontal plane, glass strips arranged under the meeting edges of said panes and secured thereto, a solution of silicate of soda applied to said joints, and stiffening trusses secured to said frame.

In testimony whereof I have hereunto set my hand in presence of two subscribing witnesses.

DWIGHT WILSON BENNETT.
